FISHING LURE

Jack A. Smithwick, P.O. Box 1285,
Shreveport, La. 71163

Filed May 23, 1975, Ser. No. 568,345

Term of patent 14 years

Int. Cl. D22—05

U.S. Cl. D22—27

FIG. 1 is a side elevation view of one embodiment of a fishing lure incorporating my new design.

FIG. 2 is a top plan view of the fishing lure shown in FIG. 1.

FIG. 3 is a bottom plan view of the fishing lure shown in FIG. 1.

FIG. 4 is a front elevation view of the fishing lure illustrated in FIG. 1, showing the lure as it appears when viewed from the forward end thereof.

FIG. 5 is a rear elevation view of the fishing lure illustrated in FIG. 1, showing the lure as it appears when viewed from the rear end thereof.

FIG. 6 is a side elevation view of a different embodiment of a fishing lure incorporating my new design.

FIG. 7 is a top plan view of the fishing lure shown in FIG. 6.

I claim:

The ornamental design for fishing lure, substantially as shown and described.
